CREEL SPINDLE FOR TWISTING MACHINES
AND THE LIKEStanley W. Burlingame, Pawtucket, R. I., assignor
to Barber-Colman Company, Rockford, Ill., a
corporation of Illinois

Application February 7, 1949, Serial No. 74,928

3 Claims. (Cl. 242—35)

1

The invention pertains in general to twisting machines of the type in which paired threads to be wound upon power driven bobbins are supplied from larger yarn masses or cheeses supported upon a creel; and it has more special reference to a novel spindle construction for supporting the cheeses on the creel.

It has heretofore been the practice to support the cheeses upon a creel equipped with slightly inclined spindles, each adapted to support a pair of cheeses with the adjacent ends of the cheese cores in frictional engagement. With the spindles thus constructed, it has been necessary to pull the threads from the paired cheeses in opposite directions due to the fact that the frictional bearing engagement between the abutting ends of the cheese cores is sufficient to cause a driving action of one of the cheeses upon the other, particularly in the case of cheeses of different diameters. On the other hand, rotation of the paired cheeses in opposite directions is objectionable because of the drag on the threads incident to the frictional engagement between the cheeses, and also because the mounting of the cheeses on the spindles so as to require the yarn strands or threads to be pulled off in opposite directions is inconvenient and time consuming.

With the foregoing in view, the object of my invention is to provide a novel spindle construction which eliminates the frictional bearing engagement between the cores of the two cheeses mounted thereon and which, therefore, permits the cheeses to be so mounted that the threads are pulled therefrom in the same direction.

Figure 1 is the front view of a twisting machine upon which the improved spindle is used;

Figure 2 is an end view of the machine shown in Figure 1;

Figure 3 is a cross sectional view of one of the spindles showing a pair of cheeses mounted thereon;

Figure 4 is an elevation of the improved spindle and

Figure 5 is an end view of a portion of the spindle showing the shoulder and eccentric tip.

In Figs. 1 and 2 of the drawings, I have shown for purposes of illustration a twisting machine generally designated 1 having a series a power driven bobbins B, to each of which paired threads are supplied from cheeses C mounted upon a creel generally designated 3, the paired threads being guided and controlled in a conventional manner. As shown, the threads pass downwardly through guides 9 and thence consecutively be-

10 tween rollers 10 and thread guides 11 to the ring rail 12.

15 The cheeses C are supported upon the creel 8 by means of fixed spindles 13 slightly inclined from the horizontal, in the conventional manner. In accordance with my invention, each spindle is constructed to support a pair of cheeses in axially spaced relation in a manner such as to avoid any frictional engagement between the 20 two cheeses while permitting of free and easy placement and removal of the cheeses on the spindle. As shown, each cheese has a central core 14 of wood, and the spindle is especially shaped to provide an inner portion 13a providing a bearing for the core of the innermost cheese, and an outer portion 13b providing a bearing for the core of the outermost cheese.

25 The inner portion 13a of the spindle is made of a diameter substantially corresponding to that of the internal diameter of the central bore of the core, but the outer end portion of the spindle is cut away at its upper side so as to form a bearing surface offset downwardly with respect to the upper surface of the portion 13a. Thus, the upper surface of the outer portion 13b is in effect disposed eccentrically with respect to the corresponding surface of the inner end portion 13a. Between the two bearing surfaces of the 30 spindle is formed a shoulder 15 for engagement by an annular bearing surface 16 at the inner end of the cheese core. As herein shown, the surface 16 is formed by the bottom of a socket 17 providing, in the case of the innermost cheese, clearance for the spindle fastening means.

35 This means may comprise a hexagonal portion 18 and a threaded stem 19 for insertion through a hole in the creel frame, the spindle being secured in position by means of a nut 20. Preferably, the outer end of the hexagonal portion 40 18 is rounded to provide a bearing shoulder 18a for engagement by the bearing surface 16 of the core.

45 It will be seen that through the provision of two bearing surfaces offset transversely with respect to each other, together with the bearing shoulders 15 and 18a, the two cheese cores are maintained in axially spaced relation free of frictional engagement between the cores. Accordingly, it is possible to mount the cheeses on the creel so as to permit the threads to be pulled from adjacent pairs in the same direction. At the same time, the construction and arrangement employed does not in any way interfere 50 with the free and easy placement or removal of

the cheeses with respect to their supporting spindles.

I claim as my invention:

1. In a twisting machine or the like having means for rotatably supporting a plurality of bobbins to be wound, means for supplying yarn to the bobbins comprising a creel having a plurality of inclined spindles each adapted to support a pair of cheeses and providing bearing surfaces transversely offset with respect to each other and terminating at their inner ends in bearing shoulders for engagement by the cheese cores, said shoulders being spaced apart axially of the spindle so as to maintain the cores in axially spaced relation.

2. A spindle for supporting a pair of cheeses for rotation on axes inclined slightly from the horizontal, comprising inner and outer portions for engagement by the cores of the respective cheeses, the outer portion of the spindle having its upper portion cut away so as to be offset downwardly from the corresponding surface of the inner portion, and a bearing shoulder at the inner end of said outer portion for engagement

by the core of the outermost cheese whereby the two cores are held in axially spaced relation.

3. A spindle for supporting a pair of cheeses for rotation on axes inclined slightly from the horizontal, comprising inner and outer portions for engagement by the cores of the respective cheeses, the outer portion of the spindle having a bearing surface offset downwardly from the bearing surface of the inner portion and terminating at its inner end in a shoulder for engagement by the core of the outermost cheese, and means at the inner end of the spindle providing a bearing shoulder for the innermost cheese.
